CLAIM

The ornamental design for a vehicle headlamp, as shown and described.

DESCRIPTION

FIG. 1 is a front view of a vehicle headlamp according to a first embodiment of the invention;

FIG. 2 is a rear view thereof;

FIG. 3 is a right side view thereof;

FIG. 4 is a left side view thereof;

FIG. 5 is a top view thereof; and,

FIG. 6 is a perspective view thereof.

A second embodiment includes the mirror image of the vehicle headlamp shown in FIGS. 1-6.

Features shown in broken lines illustrate environmental structures of the vehicle headlamp that form no part of the claimed design.

1 Claim, 6 Drawing Sheets
